WEATHER STRIP

Harry H. Goldberg, Denver, Colo.

Application January 3, 1939, Serial No. 248,942

7 Claims. (Cl. 20—69)

This invention relates to improvements in sealing means for casement windows and has reference more particularly to a weather strip that can be employed in connection with any ordinary casement window.

It is becoming increasingly popular to employ metal window frames and sash in building construction; such window construction, however, is not weather tight, as it is very difficult to effect such a close fit between the casement frame and the sash that air and dust will not enter. To make this type of window weather proof, various kinds of weather strips have been invented and used.

It is the object of this invention to produce a weather strip that can be interposed between the casement frame and a screen or storm window frame and which can be attached to the latter so that both may be applied or removed as a unit.

Another object of the invention is to produce a seal or weather strip that can be used by itself, as well as in connection with an auxiliary frame.

In order to explain this invention so that it can be readily understood, reference will be had to the accompanying drawing in which the invention has been illustrated in its preferred form, and in which:

Figure 1 is a side elevation showing a corner of a casement window with the improved weather strip in position between the casement frame and the screen frame;

Figure 2 is a section taken on line 2—2, Figure 1, portions being shown in perspective;

Figure 3 is a top plan view of the improved weather strip;

Figure 4 is a section taken on line 4—4, Figure 3; and

Figure 5 is a section similar to that shown in Figure 4, but showing the weather strip attached to a casement window without the use of the auxiliary frame.

In the drawing reference numeral 6 designates a casement frame and reference numeral 7 a window sash. These two parts are of conventional construction, each being formed from a special Z-bar having a central web 8 and flanges 9. Applicant claims no novelty in the frame construction, but the parts have been illustrated in detail for the purpose of better explaining his invention. When the window sash is closed, the parts occupy the position shown in Figure 2 from which it will be seen that the corresponding flanges of the frame and the sash overlap.

It is customary to apply to casement windows of this type a woven wire screen like that indi-

cated by reference numeral 10 in Figures 1 and 2, and this is secured to a screen frame which has been indicated in its entirety by reference numeral 11. The screen frame illustrated in the drawing is of old and well known construction, 5 but for the purpose of making this description complete, the screen frame construction will be described to some extent, as follows:

The screen frame is made from a single piece of sheet metal bent into substantially rectangular form. The top of the frame has been designated by reference numeral 12, the outer vertical side by reference numeral 13, and the bottom by reference numeral 14. The top is bent downwardly along line 15 and thence outwardly as indicated at 16 and thence downwardly as indicated at 17. The bottom is bent upwardly so as to form a side wall 18, and thence outwardly to form the bottom 19 of a longitudinally extending groove. The edge of the bottom 19 and of the side 17 overlap so as to form a rigid assembly. The screen 10 is positioned in the groove and held in place by a bar 20. Such screen frames are in common use and are secured to the casement frame by means of clips 21 of Z-shape and these 25 clips are secured to the casement frame by screws 22.

In order to effect a weather seal between the sash and the casement frame, a weather strip has been provided that has been designed with special 30 reference to the position in which it is to be used in the combination illustrated in Figures 1 and 2.

The weather strip consists of an elongated metal strip 23, which is preferably made from sheet steel, although it can be made from any 35 other suitable material, such as brass or copper. The strip is offset longitudinally so as to form two surfaces at different levels, the lower surface being indicated by reference numeral 24; the edge of the higher surface shown in Figure 4 has 40 been designated by numeral 25, and this has been bent downwardly and thence reversely so as to form a channel 26. The edge of the lower portion has been designated by reference numeral 27 and this has also been bent reversely so as to 45 form a channel 28. Resilient sealing members are attached to the edges of the weather strip 23 and interlocked with the latter by means of the reversely bent edges 25 and 27 and the corresponding channels 26 and 28. The sealing strips 50 have been designated by reference numerals 29 and 30. The sealing strip 29 is formed of a sheet of rubber, or other similar material, bent into the shape shown in Figure 4 and allowed to set in this shape, and such a strip can readily be at- 55

tached to the weather strip 23, and when so attached will be quite firmly held in place. The resilient strip 30 differs from the one marked 29 in this, that the under portion thereof is provided with an opening 31, which permits the strip to be compressed to a greater extent than if it were solid, and this makes it possible for it to accommodate itself to every irregularity in the contacting surface of the sash. The strip 23 is 10 provided with spaced openings 32 for the reception of screws 33 by means of which it may be secured to the bottom 14 of the screen frame. When a screen frame is not used, the weather strip can be attached to the casement frame in 15 the manner shown in Figure 5, in which position it can be held by screws 33a that have threaded connection with openings in the casement frame 6. When the weather strip is used in the absence of the screen or storm sash frame, ferrules 20 34 of a proper length are positioned between the under surface of the strip and the outer surface of the casement frame flange in the manner shown in Figure 5.

From the above description, when taken in 25 connection with the drawing, it will be apparent that by means of this weather strip, a weather tight seal can be provided between the window casement frame and the window sash, either with, or in the absence of the screen frame.

30 Attention is also directed to the fact that two separate resilient sealing strips are employed, one of which effects a seal with the sash and the other a parallel seal with the casement frame. Such weather strips can be manufactured in 35 suitable lengths and cut to fit any size window opening. Although they are entirely separate from the screen frame, they can be readily attached thereto in the manner shown in Figure 2, and this facilitates the application of the weather 40 strip to the casing. It is, however, possible to effect the seal in the manner shown in Figure 5 and this manner of employing the weather strip is indicated where screens are not used.

In the above, reference has been made to the 45 fact that the metal strip 23 is formed with surfaces on two levels and one of the reasons for this construction is that the resilient sealing strip 30 has a portion 35 that is reversely bent and this is positioned on top of the lower longitudinal 50 surface of the strip so that the upper surface of the weather strip will be substantially in a single plane. The outer wall of strip 29 has been shown as extending upwardly above the surface of the weather strip and it therefore overlaps 55 the vertical side 13 of the screen frame when in position. This feature of the construction is not of any considerable importance, and the vertical wall of strip 29 can be made of a height different from that shown without effecting the 60 sealing function.

Having described the invention what is claimed as new is:

1. A device for effecting a seal between a casement frame and sash, comprising a metal strip,

a sealing strip of resilient material attached along each edge thereof, said resilient strips projecting unequal distances from one surface of the metal strip, the thinner and the thicker resilient strips being adapted to contact respectively 5 with the casement frame and the sash.

2. A device for effecting a seal between a casement frame and sash, comprising a metal strip, a sealing strip of resilient material attached along each edge thereof, said resilient strips projecting unequal distances from one surface of the metal strip, the thinner and the thicker resilient strips being adapted to contact respectively 10 with the casement frame and the sash, and means forming an interlock between the metal 15 strip and the resilient strips.

3. A device for effecting a seal between a casement frame and sash, comprising a metal strip having its edges reversely bent into spaced parallel relation with one side, whereby two channels 20 are formed, and resilient sealing strips having attaching edges positioned in the channels, said strips being folded outwardly over the bent edges.

4. A device for effecting a seal between a casement frame and sash, comprising a metal strip 25 having its edges reversely bent into spaced parallel relation with one side, whereby two channels are formed, and resilient sealing strips having attaching edges positioned in the channels, said strips being folded outwardly over the bent edges, 30 one of the resilient strips being thicker than the other.

5. A sealing device for casement windows, comprising a metal strip offset transversely to form two parallel surfaces in spaced planes, the 35 edges being downwardly and reversely bent to form channels, and resilient, compressible sealing strips having portions positioned in the channels and passing over the reversely bent edges.

6. A sealing device for casement windows, 40 comprising a metal strip offset transversely to form two parallel surfaces in spaced planes, the edges being downwardly and reversely bent to form channels, and resilient compressible sealing strips having portions positioned in the channels 45 and passing over the reversely bent edges, the sealing surfaces of the resilient strips being spaced different distances from the upper surface of the metal strip.

7. A sealing device for casement windows, 50 comprising a metal strip offset transversely to form two parallel surfaces in spaced planes, the edges being downwardly and reversely bent to form channels, and resilient compressible sealing strips having portions positioned in the channels 55 and passing over the reversely bent edges, the sealing surfaces of the resilient strips being spaced different distances from the upper surface of the metal strip, the resilient strip that is attached to the edge of the depressed surface 60 of the metal strip having a portion extending inwardly over the top of the depressed surface.
